(57) **CLAIM**

The ornamental design for a cup holder adapter, as shown and described.

DESCRIPTION

FIG. 1 is a top plan view of a cup holder adapter showing our new design in the form of a blank;

FIG. 2 is top plan view of the cup holder adapter of FIG. 1 in an intermediate folded configuration;

FIG. 3 is perspective view of the cup holder adapter of FIG. 1 in its fully folded configuration;

FIG. 4 is a top plan view of a cup holder adapter showing a second embodiment of our new design in the form of a paperboard blank;

FIG. 5 is top plan view of the cup holder adapter of FIG. 4 in an intermediate folded configuration; and,

FIG. 6 is perspective view of the cup holder adapter of FIG. 4 in its fully folded configuration.

The vertically-oriented internal solid lines represent cut lines and the evenly sized dashed lines represent fold lines in FIGS. 1, 2, 4 and 5. The broken lines consisting of a long dash followed by a short dash showing of the eyelet in FIGS. 1–6 are for illustrative purpose only and form no part of the claimed design. The thickness of the blank is that of a conventional paperboard.
